US0D1091687S

(12) United States Design Patent (10) Patent No.: US D1,091,687 S
(45) Date of Patent:  Sep. 2, 2025

(54) TYPEFACE

(71) Applicant: Adobe Inc., San Jose, CA (US)
(72) Inventor: Robert Slimbach, Williams, OR (US)
(73) Assignee: Adobe Inc., San Jose, CA (US)
() Term: 15 Years
(21) Appl. No.: 29/896,415
(22) Filed: Jul. 3, 2023
(51) LOC (15) Cl. 18-03
(52) U.S. Cl. .... USPC 18/24
(58) Field of Classification Search
USPC D18/24, 26, 29, 30, 31, 33
CPC B41B 1/02; G09B 1/04; G09B 3/04
See application file for complete search history.
